ADJUSTABLE TELESCOPIC BARRICADE DEVICE

John A. Blaskiewicz, Sr., St. Louis, Mo.

Application February 14, 1958, Serial No. 715,456

5 Claims. (Cl. 256—64)

2

Figure 2 is a perspective view of the barricade illustrated in Figure 1, Figure 2 showing the several component elements thereof in their respective collapsed or telescoped positions;

Figure 3 is an end elevational view of the barricade, Figure 3 being taken substantially on the vertical plane of line 3—3 of Figure 1, looking in the direction of the arrows;

Figure 4 is a longitudinal cross-sectional view of the barricade with the component elements thereof being illustrated in their extended positions, Figure 4 being taken substantially on the vertical plane of line 4—4 of Figure 3, looking in the direction of the arrows;

Figure 5 is a longitudinal detail cross-sectional view similar to Figure 4, but illustrating the component elements of the barricade in their collapsed or telescoped positions relative to each other;

Figure 6 is a detail cross-sectional view taken substantially on the vertical plane of line 6—6 of Figure 4, looking in the direction of the arrows;

Figure 7 is a detail cross-sectional view taken substantially on the vertical plane of line 7—7 of Figure 4, looking in the direction of the arrows; and

Figure 8 is an enlarged detail cross-sectional view taken substantially on the horizontal plane of line 8—8 of Figure 2, looking in the direction of the arrows.

Referring now more specifically to Figure 1 of the drawings, reference numeral 10 designates, in general, a barricade constructed in accordance with the teachings of this invention. The barricade 10 is seen to include an outer, elongated, substantially hollow rectangular section 12 having a pair of opposed confronting open ends, a pair of longitudinally extending, substantially rectangular, laterally spaced and parallel side walls 14, 16, and a pair of longitudinally extending substantially rectangular, laterally spaced and parallel top and bottom walls 18, 20. An elongated, substantially rectangular slot 22 extends transversely through the bottom wall 20 throughout its length, the slot 22 being centrally spaced intermediate the side walls 14, 16 (see Figure 6).

Reference numeral 24 designates an elongated, substantially U-shaped tie member having a bight portion 26 from the longitudinally extending marginal edges of which upwardly project a pair of laterally spaced and substantially parallel side arms 28, 30, and each of the latter terminate in a pair of outwardly diverging flanges 32, 34, respectively. The flanges 32, 34 are welded to the bottom wall 20 adjacent one of its ends, and extends longitudinally thereagainst with the bight 26 extending for a limited distance inwardly across the slot 22 to leave the major portion thereof open.

A cylindrical hinge pin 36 extends between the side walls 14, 16 and its opposed ends project beyond the remote sides thereof at points spaced inwardly from the aforementioned one end of the outer section 12 and slightly above the longitudinal axis of each of the side walls 14, 16. The hinge pin 36 receives a substantially hollow cylindrical spacer member 38 which extends between the adjacent sides of the side walls 14, 16, the spacer member 38 being fixedly secured to the hinge pin 36 by means of a cotter pin 40.

A lock pin 42 extends between the side walls 14, 16 and its opposed ends project beyond the remote sides thereof, the lock pin 42 being disposed intermediate the aforementioned one end of the outer section 12 and the hinge pin 36 and being vertically spaced higher than the latter. A substantially hollow cylindrical spacer member 44 is telescoped over the lock pin 42, the spacer member 44 extending between the adjacent sides of the side walls 14, 16 and being connected thereto by means of a cotter pin 46.

Each of the projecting ends of the hinge pin 36 are

This invention relates to a barricade device and, more specifically, the invention pertains to a barricade for extension across roads, sidewalks, and other passageways normally traversed by vehicular or pedestrian traffic.

One of the primary objects of this invention is to provide a barricade which may be quickly and easily extended to a desired length to one operable position and which, at the same time, may be telescoped to a collapsed or inoperable condition.

Another object of this invention is to provide a standard or leg supported barricade of the type generally described above together with means for pivotally connecting one of the ends of the standards for movement from an inoperative position to an operable position, and to provide means for retaining the standards or legs locked in their respective inoperative and operative positions.

A further object of this invention is to provide a barricade formed of a plurality of telescoped members adapted for extension and retraction relative to each other with pivotally mounted supporting standards or legs whereby the barricade may be quickly collapsed and the legs folded thereagainst for storage or transportation and in the interest of the economy in space.

A further object of this invention is to provide a device of the type described in which when the extensible elements are in their retracted inoperative positions and the legs folded thereagainst, means are provided for locking these component parts in their respective inoperative positions, and wherein means are provided for holding these parts in their respective locked operative positions.

A still further object of this invention is to provide a device of the type generally referred to above in which the assembly thereof has no loose parts and in which all sub-assemblies are welded or connected by locking means such as, for example, rivets, locked nuts or cotter pins.

Still another object of this invention is to provide a barricade of the type generally described supra, which may be fabricated from steel, aluminum, magnesium, plastics, Fiberglas, or combinations thereof, or of other suitable or comparable materials, and the component elements of the barricade could be press-formed, roll-formed, cast and in some cases extruded.

This invention contemplates, as a still further object thereof, the provision of an extensible and collapsible or telescoping barricade which is non-complex in construction and assembly, inexpensive to manufacture, and durable in use.

Other and further objects and advantages of the present invention will become more evident from a consideration of the following specification when read in conjunction with the annexed drawings, in which:

Figure 1 is a side elevational view of an extensible and collapsible barricade constructed in accordance with the present invention, this view illustrating the component parts of the barricade in their operative extended positions;

threaded and pivotally receive thereon one end, respectively, of a pair of identically constructed elongated and substantially rectangular hinge plates 48, the plates 48 being held against displacement by means of lock nuts 50. To serve a function to be described, each of the plates 48 is provided with an arcuate slot 52 which extends inwardly from its upper edge and is positioned adjacent the other end thereof.

Reference numeral 54 connotes, in general, a substantially U-shaped hinge bracket which includes a bight portion 56 from the longitudinally extending marginal edges of which depend a pair of laterally spaced and substantially parallel side arms 58, 60 which terminate at their respective outer ends in diverging flanges 62, 64. As is best seen in Figures 6 and 8, the bight portion 56 is angularly inclined with respect to the flanges 62, 64.

A hinge bracket 54 is secured to each of the hinge plates 48 with the flanges 62, 64 being juxtaposed thereagainst intermediate the ends thereof and being rigidly secured thereto as by welding. As is seen in Figures 1 and 2, the flanges 62, 64 extend transversely across their respective associated hinge plates 48. A hinge leg for each of the hinge brackets 54 is generally indicated at 66 and is seen to comprise an elongated substantially hollow cylindrical member 68 having a closure wall 70 extending across one end thereof and from which projects a tongue 72 extending diametrically thereacross. Each of the tongues 72 are received within one of the hinge brackets 54, respectively, and are pivotally connected on the side walls 58, 60 on pivot pins 74.

Reference numerals 76 denote a pair of identical standards or legs which have an elongated substantially hollow cylindrical configuration. The upper ends of the standards 76 are telescoped within the cylindrical member 68 and are retained therein by lock pins 78. One of the standards 76 is provided with a radially projecting headed stud 80 adjacent the upper end thereof, and a similar headed stud 82 projects radially from the other of the standards 76 adjacent its lower end. To the former is pivotally secured at 84 one end of an elongated substantially rectangular lever 86 having a slot 88 adjacent one end thereof and a second slot 90 spaced inwardly from the slot 88. As is seen in Figure 1, with the standards 76 disposed in their operative position, the lever 86 is pivoted to extend thereacross with the stud 82 engaged within the slot 88, the lever 86 in this case acting as a cross brace to prevent movement of the standards 76 relative to each other. When the standards 76 are moved to their inoperative position, as shown in Figure 2, the levers 86 are pivoted thereagainst and extend longitudinally thereof with the stud 80 being received within the slot 90 and thereby limiting the pivotal movement of the levers 86 in one direction.

Intermediate the ends of the side walls 14, 16 are secured outwardly opening convoluted resilient support clips 92 each of which include a bight portion 94 from the ends of which project a pair of curvilinear arms 96, 98, the outer end of the latter being integrally connected with the outer end of a third curvilinear arm 100, connected by a bight 102 to a fourth curvilinear arm 104. The bights 94, 102 of each of the clips 92 are welded to the side walls 14, 16.

The other ends of the side walls 14, 16 are each slotted at 106 and cut out at 108 to serve a function to be described. The bottom wall 20, adjacent the other end of the outer member 12 is provided with a stop clamp 110. The stop clamp 110 comprises an elongated substantially U-shaped channel member having a centrally positioned bight portion 112 (see Figures 4 and 5) from which project a pair of laterally spaced and substantially parallel side arms 114, 116 which terminate in outwardly diverging flanges 118, 120 that extend longitudinally of the bottom wall 20 on each side of the slot 22 and are secured thereto as by welding. The bight portion 112 terminates at one of its ends in a down-

wardly curved cam element 122 and at its other end in an upwardly curved abutment 124.

The barricade 10 also includes a central, elongated, substantially hollow rectangular section 126 having a pair of opposed confronting open ends, a pair of longitudinally extending, substantially rectangular, laterally spaced and parallel side walls 128, 130, and a pair of longitudinally extending substantially rectangular, laterally spaced and parallel top and bottom walls 132, 134. An elongated, substantially rectangular slot 136 extends transversely through the bottom wall 134 throughout its length, the slot being centrally spaced intermediate the side walls 128, 130 (see Figure 7). The bottom wall 134, adjacent each end thereof, is provided with downwardly or outwardly expressed offset ends 138, 140.

Reference numeral 142 denotes an elongated substantially T-shaped clamp bar having a stem 144 (see Figures 4 and 6) and a crosshead 146. The crosshead 146 is fixedly secured to the offset bottom wall portion 138 with the stem thereof projecting downwardly through the slots 136 and 22, in that order, to serve a function to be described.

The side walls 128, 130 adjacent that end of the central section 126 carrying the clamp bar 142 is formed with an inwardly extending elongated slot 148 aligned with and having a width slightly greater than the outside diameter of the spacer member 38 and a cutout portion 150 having a width slightly greater than the outside diameter of the spacer member 44. The other end of the side walls 128, 130 are provided with elongated slots 152 and cutouts 154, and the expressed portion 149 of the bottom wall 136 has secured thereto the crosshead 156 of an inverted substantially T-shaped clamp bar 158 having a longitudinally extending stem 160 projecting inwardly within the central section 126.

The inner section of the barricade 10 is designated at 162 and is seen to include an elongated, substantially hollow rectangular member having a pair of opposed confronting open ends, a pair of longitudinally extending substantially rectangular, laterally spaced and parallel side walls 164, 166, and a pair of longitudinally extending substantially rectangular, laterally spaced and parallel top and bottom walls 168, 170. An elongated, substantially rectangular slot 172 extends transversely through the bottom wall 170 throughout its length, the slot 22 being centrally spaced intermediate the side walls 164, 166 (see Figure 7). The bottom wall 170, adjacent the outer end of the inner member 162 is provided with a stop clamp 174 similar to the stop clamp 110, but inverted with respect thereto. The stop clamp 174 comprises an elongated substantially U-shaped channel member having a centrally positioned bight portion 176 from which projects a pair of laterally spaced and substantially parallel side arms 178, 180. The side arms 178, 180 are secured to the adjacent sides of the side walls 164, 166 by conventional means such as, for example, welding. The bight portion 176 at its outer end terminates in a downwardly curved abutment 182, and the other end thereof terminates in an upwardly curved cam element 184.

The other end of the inner section 162 of the barricade 10 is provided with an inner tie member 186, the tie comprising an elongated substantially U-shaped channel member having a bight 188 from the longitudinally extending marginal edges of which project a pair of laterally spaced and substantially parallel side arms 190, 192, the latter being fixedly secured to the adjacent inner sides of the side walls 164, 166.

To serve a function to be described, the inner ends 70 of the side walls 164, 166 are provided with elongated slots 194 and cutouts 196, the slots 194 being in longitudinal alignment with the slots 48 formed in the side walls 128, 130, and the cutouts 196 being aligned with the cutouts 150 formed in the side walls 128, 130 of the central section 126.

A cylindrical hinge pin 200 extends between the side walls 164, 166 and its opposed ends project beyond the remote sides thereof at points spaced inwardly from the outer end of the inner section 162 and below the longitudinal axis of each one thereof. A substantially hollow cylindrical spacer member 202 is telescoped over the hinge pin 200 and extends between the adjacent sides of the side walls 164, 166, the spacer member being pivotally secured to the hinge pin 200 by means of a cotter pin 204. Between the outer ends of the inner sections 162 and the hinge pin 200 and vertically spaced thereabove is a lock pin 206 which extends between the side walls 164, 166 and projects beyond the remote sides thereof. A substantially hollow cylindrical spacer member 208 is telescoped over the lock pin 206 and extends between the adjacent sides of the side walls 164, 166 and is connected to the lock pin 206 by means of a cotter pin 210.

One end of a pair of hinge plates 212 is pivotally connected, respectively, on the outer ends of the hinge pin 200 and is held against displacement by means of the lock nuts 214. The other ends of the hinge plates 212 are each provided with an arcuate slot 216, the function of which will be set forth below.

Reference numeral 218 connotes, in general, a substantially U-shaped hinge bracket which includes a bight portion 220 from the longitudinally extending marginal edges of which extend a pair of laterally spaced and substantially parallel side arms 222, 224 which terminate at their respective outer ends in diverging flanges 226, 228, respectively. As is best seen in Figure 7, the bight portion 220 is angularly inclined with respect to the flanges 226, 228.

A hinge bracket 218 is secured to each of the hinge plates 212 with the flanges 226, 228 being juxtaposed thereagainst intermediate the ends thereof and being rigidly secured thereto as by welding. As seen in Figures 4 and 7, the flanges 226, 228 extend transversely across their respective associated hinge plates 212.

A hinge leg for each of the hinge brackets 218 is generally indicated at 230 and is seen to comprise an elongated substantially hollow cylindrical member 232 having a closure wall 234 extending across one end thereof and from which projects a tongue 236 extending substantially diametrically thereacross. Each of the tongues 236 is received within one of the hinge brackets 218, respectively, and is pivotally connected on the side walls 222, 224 on pivot pins 238.

Reference numerals 240 denote a pair of identical standards or legs which have an elongated substantially hollow cylindrical configuration. The upper ends of the standards 240 are telescoped within the cylindrical members 230 and are retained therein by lock pins 242.

One of the standards 240 is provided with a radially projecting headed stud 243 adjacent the upper end thereof, and a similar headed stud 244 projects radially from the other of the standards 240 adjacent its lower end.

To the former is pivotally secured one end of an elongated substantially rectangular lever 246 having the same configuration as the lever 86 previously described. The lever 246 has formed therein adjacent the other end thereof a slot (not shown) to receive the stud 244 in order to hold the standards 240 against movement relative to each other.

Having described and illustrated one embodiment of this invention in detail, its operation is deemed to be manifest. However, a brief description thereof is set forth below.

Let it be assumed that the barricade 10 is in its extended position as is illustrated in Figure 1, the operator pushes the inner section 162 inwardly towards the central section 126 causing stop clamp 174 to become disengaged from the clamp bar 160, and as this movement takes place the outer ends of the lock pin 206 enters the cutouts 154 and the outer ends of the hinge pin 200

enter the slots 152 thereby limiting the extent of the inner section 162 into the central section 126. At this point, the slots 148, 194 and cutouts 150, 196 are juxtaposed in side-by-side relation.

- 5 The inner section 162 and the central section 126 are then pushed into the outer section 12 causing the clamp bar 142 to disengage the stop clamp 110. As this movement is continued, the outer ends of the lock pin 206 is received within the cutouts 108 and the outer ends of the hinge pin 200 enter the slots 106. Substantially simultaneously therewith, the juxtaposed slots 148, 194 and cutouts 150, 196 receive the outer ends of the hinge pin 36 and lock pin 42, respectively. Thus, the barricade 10 is collapsed with the component elements thereof assuming their respective positions as is illustrated in Figure 2. The levers 86 and 246 are now disengaged from the studs 82 and 244 and are pivoted to axial extension with respect to the standards 76 and 240 on which they are pivotally connected with the stud 80 being received within the slot 90 of the lever 86 and the stud 243 being received within a similar slot (not shown) in the lever 246. The standards 76 and 240 are now pivoted inwardly towards each other on each side of the barricade 10 for reception within the brackets 92 as illustrated in Figure 2.

To effect extension of the barricade the above procedural steps are carried out, substantially, in reverse. That is, the standards 76 and 240 are released from the brackets 92 and pivoted in the opposite direction in such a manner as to cause the opposite ends of the lock pins 42, 206 to enter the recesses 52, 216 formed in the hinge plates 48 and 212, respectively. With the standards 76, 240 so extended, the levers 86, 246 are pivoted to their operative position as shown in Figure 1, the levers receiving the studs 82 and 244, respectively.

The inner section 162 is now drawn outwardly of the central section 126 to effect re-engagement of the stop clamp 176 with the clamp bar 142. Relative movement between the inner section 162 and the outer section 126 ceases upon engagement of the downwardly curved portion 182 of the stop clamp 174 with the inner end of the clamp bar 142. Continued movement of the inner section 162 causes the central section 126 to slide outwardly of the outer section 12. The relative movement between the outer section 12 and the central section 126 is limited upon the re-engagement of the outer end of the clamp bar 142 with the upwardly turned end portion 124 of the stop clamp 110. The component elements of the barricade 10 have now assumed their respective positions as is illustrated in Figures 1 and 4.

Having described and illustrated one embodiment of this invention in detail, it will be understood that the same is offered merely by way of example, and that this invention is to be limited only by the scope of the appended claims.

What is claimed is:

1. An expandable and collapsible barricade comprising, in combination, a plurality of elongated substantially hollow tubular sections telescoped one inside another, means for limiting the inward telescoping movement of said sections relative to each other, a pair of standards connected to a first pair of opposed sides, respectively, of the outermost one of said sections, and a pair of standards connected to a pair of second opposed sides, respectively, of the innermost one of said sections; that improvement which comprises providing in a pair of opposed sides of the innermost ones of said telescoped sections an axially extending slot opening towards one end of said barricade, providing in a pair of opposed sides of said outermost one of said sections and succeeding innermost ones thereof axially extending slots opening towards the other end of said barricade and vertically spaced from said first slots, said means comprising a pin extending transversely between and supported on said first opposed sides of said outermost one of said sections

and disposed in confronting relation relative to said first slots and a second pin extending transversely between and supported on said opposed sides of said innermost one of said sections and disposed in confronting relation relative to said second slots, said pins being receivable within said slots to limit the inward movement of said sections relative to each other, and said standards having one of their respective ends connected on opposed ends of the adjacent one of said pins.

2. An expandible and collapsible barricade as defined in claim 1, and means pivotally connecting said one ends of said standards to said outermost and innermost ones of said sections.

3. An expandible and collapsible barricade as defined in claim 2, and a second pin extending through and supported on said opposed sides of said outermost and innermost ones of said sections and disposed in the pivotal path of movement of said standards to limit the movement thereof in one direction.

4. An expandible and collapsible barricade as defined in claim 3, and clamping means on said opposed sides of said outermost one of said sections to releasably secure thereto said standards when pivoted to their respective inoperative positions.

10

15

5. An expandible and collapsible barricade comprising, in combination, a plurality of elongated substantially hollow tubular sections telescoped one inside another, means for limiting the outward telescoping movement of said sections relative to each other, a pair of standards connected to the opposite sides of the innermost and outermost ones of said telescoped sections; that improvement in said means which comprises the provision of a stop clamp on the adjacent ends of said innermost and outermost sections including an abutment for each of said clamps, and a pair of clamp bars each disposed, respectively, adjacent opposed ends of a central one of said telescoped sections, said clamp bars slidably engaging said stop clamps and abutting against said abutments to limit the outward movement of said sections relative to each other.
